UNITED STATES PATENT OFFICE.

JOHN A. STEWARD, OF RUTLAND, VERMONT.

CAN-SEAMING MACHINE.

No. 821,134.

Specification of Letters Patent.

Patented May 22, 1906.

Application filed January 11, 1905. Serial No. 249,608.

To all whom it may concern:

Be it known that I, JOHN A. STEWARD, a citizen of the United States, residing at Rutland, in the county of Rutland, State of Vermont, have invented certain new and useful Improvements in Can-Seaming Machines, of which the following is a specification, reference being had therein to the accompanying drawings.

10 This invention relates to a can-seaming machine, and is particularly adapted for use in the production of double-seamed cans of angular, curved, or irregular shapes.

15 The invention has for an object to provide an improved construction of the seaming-head from which the seaming-rollers are controlled by means of a cam carried therein and actuating-fingers for throwing said rollers into an operative position.

20 A further object of the invention is to provide an improved construction of the driving means for the seaming-head and actuating-fingers therefor, whereby the head may be rotated and the fingers automatically thrown into operative position relative to the rotation of the head.

25 Another object of the invention is to provide an improved construction of supporting-table for the work by which the latter is raised into operative relation with the seaming-rollers and the driving-gear for said rollers thrown into driving position.

30 Other and further objects and advantages of the invention will be hereinafter set forth and the novel features thereof defined by the appended claims.

35 In the drawings, Figure 1 is an elevation of the complete machine; Fig. 2, a vertical section of the seaming-head and driving connections therefor; Fig. 3, a detail perspective of a supporting-shoe for the seaming-fingers; Fig. 4, a similar view of the seaming-head casting; Fig. 5, a perspective of the seaming-cam; Fig. 6, a similar view of a modified form of 40 said cam for circular cans; Fig. 7, a perspective of one of the seaming-fingers; Fig. 8, a side elevation of the carrier for said fingers mounted within the shoe; Fig. 9, a perspective of the holding-arm for supporting the 45 seaming-cam shaft in a fixed position within the rotating head; Figs. 10, 11, and 12, side views of the respective seaming-rollers for producing a double seam; Fig. 13, an elevation of the controlling-fingers for said rollers;

Fig. 14, a perspective of the block for supporting the seaming-rollers; Fig. 15, a similar view of a slide carried by the block and upon which the rollers are mounted; Fig. 16, a vertical section through the block and slide assembled in the head; Fig. 17, an elevation of the controlling-cam for governing the reciprocatory movement of the fingers; Fig. 18, a section through the driving-shaft for the controlling-cam, showing in elevation the clutch and tripping means therefor; Fig. 19, a detail elevation of the same parts; Fig. 20, a detail of the clutch-pin; and Fig. 21 an elevation, with parts broken away, of the controlling-lever for the machine and its connection with the can-table shaft.

Like letters of reference refer to like parts in the several figures of the drawings.

The letter A designates a standard having the base A' and provided at the upper portion with a supporting-arm A². Below this arm a second supporting-arm A³ is disposed and provided with a suitable bearing-box adapted to support the seaming-head and the shoe for the fingers. At the lower portion of the standard arms A⁴ and A⁵ are provided for the support of the shaft of the can-table. At the opposite side of the machine a yoke portion A⁶ is formed and provided with any desired number and arrangement of bearings for supporting the driving mechanism for the entire machine. These parts may be altered at will in accordance with the arrangements of the machine.

A supporting-shaft B is mounted within the arms A² and A³ and carries at its lower end a seaming-cam C. This shaft is held against rotation by means of an arm B' at its upper portion pivotally mounted upon a projecting lug A⁷ from the bracket A² by means of a cross-pin B² and provided at its free end with spring members B³, adapted to be clamped into holding contact with the upper end of the shaft B, while the pivot B' is disposed in the ears B⁴, which embrace the lug A⁷. The cam C at the lower end of the shaft B rests against a shoulder B⁵ and is clamped in position by means of a nut B⁶, disposed upon the threaded end of the shaft. This cam is of any desired formation suitable for the configuration of the can to be formed and is provided with a central aperture C', through which the shaft B extends, while surrounding this aperture is the ear or track

way C^2 , within which the seaming-cam rollers travel. The form of seaming-cam shown in Fig. 5 is adapted for operation upon a substantially oval can, while the modified form 5 (shown at C^3 in Fig. 6) is provided with a circular path C^4 for operation upon a can of similar configuration.

Surrounding the fixed shaft B is a tubular driving-shaft D, having keyed thereon a bevel-gear D', which meshes with a co-operating pinion D'', carried upon the driving-shaft D'', which is continuously rotated. The upper end of the tubular shaft D is provided with a bearing-nut D', threaded thereon and having a bearing upon the upper face of the bracket A², while the shaft B is provided with an independent nut B', threaded upon its upper end beneath the arm B'. At the lower end of the tubular shaft D the seaming-head 20 D⁵ is mounted in any desired manner—for instance, by threading thereon. This head is shown in detail in Fig. 4 and is provided with an interior recess D⁶ to receive the seaming-cam C and to rotate around the same. The 25 head is also provided with a circumferential flange D⁷, having slotted ways D⁸ therein and bearing-seats D⁹ at the body of the head for the purpose of mounting the blocks E upon the head for a reciprocatory motion relative 30 to the cam.

The block E is provided with a tubular stem E', extending through the slotted ways B⁸, and at its inner end is provided with a bearing-socket E'', adapted to receive a friction-roller E³, disposed in the cam or way carried by the fixed shaft B. As shown in Figs. 14 and 16, this block is provided at opposite sides with flanges E⁸, disposed in suitable grooves or ways D¹⁰ within the head D⁵, 40 while the under surface of the head is further provided with oppositely-disposed flanges E⁴ to provide a track or way for the roller-carrier, which is slidingly mounted therein. The outer end of the block E is provided with a depending portion E⁵, adapted to carry suitable stop devices to co-operate with the independent member F' of the roller-carrier. For instance, a set-screw E⁶ may be threaded through the portion E⁵ and held in position 45 by a lock-nut E⁷, while the travel of the member F' is limited by means of a stop-pin F², threaded therein and extending through an aperture in the portion E⁵, whereby the outward movement of the member F' acts as a cushioning device in the movement of the roller-carrier and for that purpose is provided with a cushion-block F³, of rubber or other suitable material, disposed within a recess in the member F' and provided with a contact-plate F⁴, against which the set-screw E⁶ bears. This member is also provided with a contact-roller F⁵, mounted upon the inner face thereof, where it is adapted to engage a cam-finger G, to be hereinafter described. The carrier 60 F is provided upon its face adjacent to this

finger with a similar roller F⁶, as shown by detail in Fig. 15, while the opposite end of the carrier F is formed with a recess F⁷, within which the seaming-roller H is pivotally mounted by means of a pin or journal F⁸. As usual in this art, these rollers are made of different configurations, as shown at H in Fig. 10, H' in Fig. 11, and H² in Fig. 12, so as to successively accomplish the different seaming actions in their operation upon the can. 75

As shown in Fig. 1, a series of the blocks and roller-carriers are mounted upon the head and controlled by the cam, three being shown in the present illustration; but the number thereof may be varied to suit the character 80 of work. The blocks supporting the roller-carriers are actuated by the cam C in fixed position within the head; but the carriers themselves are rendered operative successively by means of the fingers G, connected 85 to a shoe having arms I, which are carried at the lower portion of a tubular sleeve I', surrounding the driving-sleeve D of the head and adapted for a reciprocatory motion thereon in a vertical plane, said sleeve 90 being controlled by the shipper-lever I², connected in the usual manner at I³ with a pivot upon the ring I⁴, threaded upon the upper end of the tubular stem. The arms I are provided with grooves or ways I⁵, with- 95 in which the carrier-sleeves I⁶ are mounted for a reciprocatory motion in a horizontal plane coincident to the motion imparted to the block by the cam within the head, and said sleeves are retained against a vertical 100 movement within the arms by means of the flanges I⁷ at opposite sides thereof, Fig. 8. The cam-fingers G are provided with a stem G', disposed within the tubular portion E' of the block and provided at their upper ends 105 with a reduced portion G², disposed within the recess I⁸ of the sleeve and held therein by means of a nut G³, as shown in Fig. 2. For the purpose of retaining these parts against rotation the reduced portion G² of 110 the fingers G is provided with a pin or lug G⁴, adapted to seat within a recess I⁹, extending laterally from the aperture I¹⁰ through the sleeve, as will be seen by reference to Figs. 7 and 8. The fingers G are pivotally 115 secured to the lower end of the stem G' by means of the ears G⁵, extending downward therefrom, and a pivot-pin G⁶, extending therethrough and through a portion of the finger. Each of the fingers used in the series of rollers is provided with a cam or wedge face G⁷, and this face is disposed at different points intermediate of the opposite ends of the finger, as shown by reference to Fig. 13, so that when the portion G⁷ acts 120 upon the roller-carrier to force the roller into operative position the rollers will be successively moved into position in the continued downward movement of the arm controlling the same, and after each of the cam-faces G⁷ 125 130

passes the bearing-rollers upon the seaming-roller carrier the parts are released, so as to have no further action upon the can. In the operation of the invention only one of the 5 seaming-rollers is in operation at a time, and as the seaming-rollers perform successive steps in forming the double seam they are successively operated by the disposition of the cam-faces upon the fingers G, as just described.

The shipper-lever I² may be operated in any desired manner, but is preferably automatically controlled by means of a cam J, Fig. 7, of suitable configuration to govern 15 the successive downward movement of the arms controlling the cam-fingers, said cam being mounted upon a driving-shaft J', as shown in Fig. 1. Coöoperating with this cam is a friction-roller J², carried by a casing J³, supported upon one end of the shipper-lever I², which lever is pivoted at J⁴ upon a suitable support—for instance, lugs from the standard A, as shown in Fig. 1—and this roller is held in contact with the cam by 20 any suitable tension means—for instance, a weight J⁵, suspended by means of a rod J⁶, pivotally connected with the casing J³, as at J'. 25

For the purpose of reducing the speed of the driving-shaft J' below that of the shaft 30 D³, as shown in Fig. 1, a series of reducing-gears of any desired arrangement may be provided. For instance, motion may be conveyed from a pulley K upon the driving-shaft D³ to a larger pulley K' upon the shaft K² by 35 means of a belt K³. The shaft K² carries a pinion K⁴, meshing with a gear K⁵ upon the shaft K⁶, which shaft has secured thereto a pinion K⁷, meshing with a gear K⁸ upon the shaft K⁹. This latter shaft is provided with 40 a pinion K¹⁰, meshing with a gear L, loosely mounted upon the shaft J' and adapted to be secured to rotate with said shaft by means to be hereinafter described. These means may comprise any suitable trip or clutch 45 mechanism; but a desirable form is herein illustrated in Figs. 18 and 19, wherein the gear L is provided at one side with a hub L', having secured thereon a hardened plate L³, provided with a series of recesses L² extending 50 therethrough and into the hub L'. These recesses are adapted to receive the clutch-pin L⁴, mounted to reciprocate within the hub M, secured to the shaft J'. This pin is provided with a head L⁵ and with a guide- 55 stem L⁶, extending through a suitable recess in the hub and parallel to the pin L⁴ for the purpose of guiding the same and preventing any rotation thereof. The clutch-pin is normally held in one of the sockets in the hub 60 L' by means of a tension-spring L⁷, mounted upon a face of the hub M in any desired manner—for instance, by the screws L⁸—and bearing at its free end upon the head L⁵ of the clutch-head. The inner face of this pin is 65 tapered or beveled, as shown at L⁹, to coöp-

erate with the beveled face N of the clutch-finger N'. This finger is mounted in a bracket N² by means of a pivot N³ and the beveled end thereof normally forced toward the shaft J' by means of a tension-spring N⁴, 70 secured at one end to the bracket and bearing at its opposite end against the lower portion N⁵ of the clutch-finger N'.

During the operation of seaming a can the gear L and the members carried by the shaft J' make one revolution, and for the purpose of controlling this motion and for automatically releasing the controlling-cam a trip-lever O is provided and comprises substantially a bell-crank lever having one end O' 75 thereof provided with a pivotally-mounted friction-roller O² and the opposite end O³ connected, by means of a link or rod O⁴, with the controlling-lever of the machine, to be hereinafter described. Depending from this bell-crank lever is an arm O⁵, provided with a laterally-extending pin O⁶, which in the movement of the lever in the direction indicated by the arrow in Fig. 18 contacts with the lower end of the trip-finger N', withdrawing 80 it from the clutch-pin, which is forced by the tension-spring upon the head thereof into clutching contact with the hub of the continuously-driven gear L, thus imparting movement to the shaft J' and to the controlling-cam J, carried thereby. In this motion of the crank-lever the friction-roller is raised 85 to ride upon the cam-flange M', carried by the hub M and holds the parts in this position until a complete rotation is made, when 90 the recessed portion M² of the flange permits the parts to be retracted to the position shown in Fig. 18, when the finger N' is disposed in the path of the head L⁵ and automatically passes behind the same to withdraw the pin 95 from the hub of the driven gear L, thus disconnecting the shaft J' from its driving means. The controlling-lever for the parts just described is shown at P in Figs. 1 and 21 and is connected with the link or rod O⁴ by means 100 of a bell-crank lever O⁷, mounted upon a fixed part and connected by a link O⁸ with the controlling-lever at the pivot P', which is disposed above the pivot P² for said lever. The latter pivot is mounted in a depending bracket 105 P³, carried by the arm A⁵, which forms one of the bearings for the shaft Q of the can-table Q'. This shaft is provided at its lower portion with a collar Q², secured thereon by any suitable means—for instance, a set-screw Q³—110 and is provided at opposite sides with pivots Q⁴, by which it is connected with the outer end of a lever Q⁵, pivotally mounted at its inner end Q⁶ to the standard A. This lever is provided intermediate of its ends with a pin or 115 lug Q⁷, adapted to engage a cam-lever P⁴, carried by the controlling-lever P, which in its movement carries the pin Q⁷ and the lever upon which it is mounted from the full-line position shown in Fig. 21 to that shown 120 125 130

in dotted lines, thus bringing the can into firm contact with the seaming-head. The lever P is automatically retracted by means of the spring P⁶, extending therefrom to the standard. After the raising operation is performed there is a continued movement of the lever P permitted for the purpose of tripping the clutch-pin and starting the operating-shaft for the controlling-cam. Referring to Fig. 21, the position indicated at 1 is with the parts at rest, at which time the seaming-head is continuously rotated in the usual manner. When the lever is brought to the position indicated at 2, the table is elevated to bring the can into the seaming-head, while a continued movement to the position shown at 3 trips the clutch to operate the controlling-cam, which is rotated at a much slower speed than the seaming-head and makes only a single revolution during the time required for the several seaming-rollers to consecutively operate upon the can to be seamed.

It is believed that the operation of the different features of construction will be clearly understood from the foregoing description, and it need only be added that in the use of the machine the can is placed upon its table and the shaft therefor raised by the controlling-lever to bring the can into the seaming-head and against the stop at that point. This movement does not start the controlling-cam, and the can can be lowered again if found necessary as a continued movement of the lever in the same direction is required to trip the finger controlling the clutch-pin, so as to permit that pin to seat in the continuously-rotated gear loosely mounted upon the same shaft. When this gear is clutched, it rotates the shaft and the controlling-cam secured thereto, while the configuration of this cam determines the successive downward movement of the cam-fingers, by which each of the seaming-rollers is consecutively placed in operative position relative to the can and after this operation allowed to retract therefrom. This action continues until the cam-flange at the tripping-finger has completed a revolution, when the clutch-pin is automatically withdrawn, thus stopping the rotation of the controlling-cam in proper position to permit the elevation of the cam-fingers by means of the weight or other retracting means connected to the tripping-lever, by which the fingers are reciprocated. It will be observed that the operation of these fingers is independent of the continuous rotation of the head, while the rollers are not operative until the fingers are thrown into proper position by the controlling-cam. The pattern-cam, held in fixed position within the head, is capable of removal or replacement, as found necessary, and controls the reciprocatory motion of the carriers for the seaming-rollers, so that any desired configuration of can may be seamed simply by

changing this pattern-cam within the seaming-head. It is only necessary to operate the controlling-lever by hand in one direction, so as to raise the roller-carried by the bell-crank lever upon the periphery of the cam-flange, which will hold the lever and other parts in operative position during the rotation of this flange, and when the recessed portion of the flange is reached the lever is automatically restored to its inward position by means of the retracting-spring extending from the lever to the standard.

It will be obvious that changes may be made in the details of construction and configuration such as would be suggested by the foregoing disclosure to those skilled in this art without departing from the spirit of the invention as defined by the appended claims.

Having described my invention and set forth its merits, what I claim, and desire to secure by Letters Patent, is—

1. In a seaming-machine, a seaming-head, roller-carriers slidably mounted therein, a pattern-cam carried by the head and connected to the carriers to control the movement of said carriers and means for successively retaining said carriers in operative position.

2. In a seaming-machine, a seaming-head, roller-carriers, slidably mounted therein, a pattern-cam carried by the head and connected to the carriers to control the movement of said carriers, and cam-fingers constructed to successively retain said carriers in operative position.

3. In a seaming-machine, a seaming-head, roller-carriers slidably mounted therein, a pattern-cam carried by the head and connected to the carriers to control the movement of said carriers, cam-fingers constructed to successively retain said carriers in operative position, and arms to control the reciprocation and radial travel of said fingers.

4. In a seaming-machine, a seaming-head, roller-carriers slidably mounted therein, a pattern-cam adapted to control the movement of said carriers, cam-fingers constructed to successively retain said carriers in operative position, arms to control the reciprocation of said fingers, and a controlling-cam to impart a progressive movement to said arms.

5. In a seaming-machine, a seaming-head, roller-carriers slidably mounted therein, a pattern-cam adapted to control the movement of said carriers, cam-fingers constructed to successively retain said carriers in operative position, arms to control the reciprocation of said fingers, a controlling-cam to impart a progressive movement to said arms, and a shipper-lever extending from said arms to said controlling-cam.

6. In a seaming-machine, a seaming-head, roller-carriers slidably mounted therein, a pattern-cam adapted to control the movement of said carriers, cam-fingers construct-

ed to successively retain said carriers in operative position, arms to control the reciprocation of said fingers, a controlling-cam to impart a progressive movement to said arms, 5 a shipper-lever extending from said arms to said controlling-cam, a controlling-lever, and means connected therewith for driving said controlling-cam for a single rotation.

7. In a seaming-machine, a seaming-head, 10 roller-carriers slidably mounted therein, a pattern-cam adapted to control the movement of said carriers, cam-fingers constructed to successively retain said carriers in operative position, arms to control the reciprocation of said fingers, a controlling-cam to impart a progressive movement to said arms, 15 a shipper-lever extending from said arms to said controlling-cam, a controlling-lever, means connected therewith for driving said controlling-cam for a single rotation, and a 20 can-table operatively connected to said lever to be raised into position prior to the operation of the driving means for the controlling-cam.

25 8. In a seaming machine, a seaming-head, roller-carried slidably mounted therein, a pattern-cam adapted to control the movement of said carriers, cam-fingers constructed to successively retain said carriers in operative position, arms to control the reciprocation of said fingers, a controlling-cam to impart a progressive movement to said arms, 30 a shipper-lever extending from said arms to said controlling-cam, a controlling-lever, means connected therewith for driving said controlling-cam for a single rotation, a can-table operatively connected to said lever to be raised into position prior to the operation 35 of the driving means for the controlling-cam, and means for rotating said seaming-head and parts carried thereby relative to the fixed pattern-cam.

9. In a seaming-machine, a seaming-head, 40 roller-carriers slidably mounted therein, a pattern-cam adapted to control the movement of said carriers, cam-fingers constructed to successively retain said carriers in operative position, arms to control the reciprocation of said fingers, a controlling-cam to 45 impart a progressive movement to said arms, a shipper-lever extending from said arms to said controlling-cam, a controlling-lever, means connected therewith for driving said controlling-cam for a single rotation, a can-table operatively connected to said lever to be raised into position prior to the operation 50 of the driving means for the controlling-cam, means for rotating said seaming-head and parts carried thereby relative to the fixed 55 pattern-cam, and means for restoring said shipper-lever to its initial position after a single rotation of the controlling-cam.

10. In a seaming-machine, a seaming-head, 60 provided with a rotatable bearing-sleeve,

means for driving said sleeve, a fixed supporting-shaft within said sleeve, a pattern-cam secured to said supporting-shaft within the seaming-head, and a slide-block mounted for reciprocation in said head and having means extending into the path of said cam. 65 70

11. In a seaming-machine, a seaming-head provided with a rotatable bearing-sleeve, means for driving said sleeve, a fixed supporting-shaft within said sleeve, a pattern-cam secured to said supporting-shaft within 75 the seaming-head, a slide-block mounted for reciprocation in said head and having means extending into the path of said cam, a seaming-roller carrier slidably mounted in said head and composed of separate sections, and 80 a cam-finger mounted for insertion between said sections to hold the roller in operative position.

12. In a seaming-machine, a seaming-head provided with a rotatable bearing-sleeve, 85 means for driving said sleeve, a fixed supporting-shaft within said sleeve, a pattern-cam secured to said supporting-shaft within the seaming-head, a slide-block mounted for reciprocation in said head and having means 90 extending into the path of said cam, a seaming-roller carrier slidably mounted in said head and composed of separate sections, a cam-finger mounted for insertion between 95 said sections to hold the roller in operative position, a cushion-block disposed upon one member of said carrier, and a set-screw carried by the slide-block to bear upon said cushion.

13. In a seaming-machine, a seaming-head 100 provided with a rotatable bearing-sleeve, means for driving said sleeve, a fixed supporting-shaft within said sleeve, a pattern-cam secured to said supporting-shaft within the seaming-head, a slide-block mounted for reciprocation within said head and having means extending into the path of said cam, a seaming-roller carrier slidably mounted in 105 said head and composed of separate sections, a cam-finger mounted for insertion between said sections to hold the roller in operative 110 position, a cushion-block disposed upon one member of said carrier, a set-screw carried by the slide-block to bear upon said cushion, and a stop-pin carried by a member of the 115 carrier and extending through a wall of said slide-block.

14. In a seaming-machine, a seaming-head, 120 a seaming-roller carrier slidably mounted thereon, fingers for retaining said carrier in operative position, a sleeve provided at its lower end with arms connected to said fingers, a pattern-cam connected to shift said carrier and fingers relatively to the head, and means for reciprocating said sleeve upon the 125 shaft of the seaming-head.

15. In a seaming-machine, a seaming-head, 130 a seaming-roller carrier slidably mounted

- thereon, fingers for retaining said carrier in operative position, a sleeve provided at its lower end with arms connected to said fingers, a pattern-cam connected to shift said carrier and fingers relatively to the head, means for reciprocating said sleeve upon the shaft of the seaming-head, and a bearing-sleeve mounted upon the upper end of said fingers and adapted to slide in a slot within 10 said arms.
16. In a seaming-machine, a seaming-head, a seaming-roller carrier slidably mounted thereon, fingers for retaining said carrier in operative position, a sleeve provided at its lower end with arms connected to said fingers, means for reciprocating said sleeve upon the shaft of the seaming-head, a bearing-sleeve mounted upon the upper end of said fingers and adapted to slide in a slot within 15 said arms, a stem pivotally mounted upon said fingers, and means at the upper portion of said stem to hold the bearing-sleeve against rotation.
17. In a seaming-machine, a supporting-shaft, means carried by the frame of the machine for holding said shaft against rotation, a tubular driving-shaft surrounding said supporting-shaft and provided with a bearing-nut at its upper end, a seaming-head carried 25 by the lower end of said tubular shaft and having an interior recess therein, a pattern-cam disposed within said recess, and a nut disposed upon the lower end of said supporting-shaft for retaining said cam in position.
18. In a seaming-machine, a supporting-shaft, means carried by the frame of the machine for holding said shaft against rotation, a tubular driving-shaft surrounding said supporting-shaft and provided with a bearing-nut at its upper end, a seaming-head carried 30 by the lower end of said tubular shaft and having an interior recess therein, a pattern-cam disposed within said recess, a nut disposed upon the lower end of said supporting-shaft for retaining said cam in position, a slotted flange extending from the seaming-head, a slide-block provided with a tubular stem disposed within the slot of said flange, and a friction-roller carried by said block and 35 disposed in the path of said pattern-cam.
19. In a seaming-machine, a supporting-shaft, means carried by the frame of the machine for holding said shaft against rotation, a tubular driving-shaft surrounding said supporting-shaft and provided with a bearing-nut at its upper end, a seaming-head carried 40 by the lower end of said tubular shaft and having an interior recess therein, a pattern-cam disposed within said recess, a nut disposed upon the lower end of said supporting-shaft for retaining said cam in position, a slotted flange extending from the seaming-head, a slide-block provided with a tubular stem disposed within the slot of said flange, and a friction-roller carried by said block and 45 disposed in the path of said pattern-cam.
20. In a seaming-machine, a slide-block, a roller-carrier mounted to reciprocate thereon and comprising independent members, friction-rollers carried by the adjacent faces of said members, and a finger mounted to reciprocate between said rollers.
21. In a seaming-machine, a seaming-head, a series of roller-carriers mounted to reciprocate thereon, a reciprocatory member provided with fingers constructed and arranged to consecutively hold said carriers in operative position and to travel therewith radially of said member, and a controlling-cam to impart motion to said fingers.
22. In a seaming-machine, a seaming-head, a series of roller-carriers mounted thereon a reciprocatory member provided with fingers constructed and arranged to consecutively hold said carriers in operative position, a controlling-cam to impart motion to said fingers, driving means and clutch connections for said cam, a can-table beneath said rollers, and controlling means constructed and arranged to primarily raise said table into operative position and subsequently clutch and automatically unclutch said controlling-cam with its driving means.
23. In a seaming-machine, a seaming-head, a series of roller-carriers mounted thereon, a reciprocatory member provided with cam-fingers constructed and arranged to consecutively hold said carriers in operative position, a controlling-cam to impart motion to said fingers, a can-table beneath said rollers, controlling means constructed and arranged to primarily raise said table into operative position and secondarily to connect said controlling-cam with its driving means, a pattern-cam carried within said head, and means extending from said pattern-cam to control the reciprocation of the roller-carriers.
24. In a seaming-machine, a seaming-head, a series of roller-carriers mounted thereon, a reciprocatory member provided with cam-fingers constructed and arranged to consecutively hold said carriers in operative position, a controlling-cam to impart motion to said fingers, a can-table beneath said roller-carriers, controlling means constructed and arranged to primarily raise said table into operative position and secondarily to connect said controlling-cam with its driving means, a pattern-cam carried within said head, means extending from said pattern-cam to control the reciprocation of the roller-carriers, and means for automatically releasing

the controlling-cam from its driving means and lowering the can-table after a complete rotation of the controlling-cam.

25. In a seaming-machine, a seaming-head, 5 a series of roller-carriers mounted thereon, a reciprocating member provided with cam-fingers constructed and arranged to consecutively hold said carriers in operative position, a controlling-cam to impart motion to said fingers, a can-table beneath said roller-carriers, controlling means constructed and arranged to primarily raise said table into operative position and secondarily to connect said controlling-cam with its driving means, 15 a pattern-cam carried within said head, means extending from said pattern-cam to control the reciprocation of the roller-carriers, means for automatically releasing the controlling-cam from its driving means and 20 lowering the can-table after a complete rotation of the controlling-cam, and means for continuously rotating the seaming-head relative to the pattern-cam and at a greater speed than the rotation of the controlling- 25 cam.

26. In a seaming-machine, a seaming-head, seaming-rollers mounted to reciprocate therein, fingers to control said rollers and travel therewith, a shoe provided with radiating 30 slotted arms, and a carrier for said fingers disposed to travel radially within said arms and provided with flanges upon its opposite ends.

27. In a seaming-machine, a seaming-head, seaming-rollers mounted therein, fingers for 35 controlling said rollers, a shoe provided with radiating slotted arms, a carrier for said fingers disposed within said arms and provided with flanges upon its opposite ends, and an interlocking projection between said fingers 40 and carrier to prevent relative rotation thereof.

28. In a seaming-machine, a seaming-head, seaming-rollers mounted therein, fingers for controlling said rollers, a shoe provided with 45 radiating slotted arms, a carrier for said fingers disposed within said arms and provided with flanges upon its opposite ends, an interlocking projection between said fingers and carrier to prevent relative rotation thereof, a cam portion at the lower end of said fingers, and a pivotal connection between said portion and the upper end of the fingers.

29. In a seaming-machine, a seaming-head, seaming-rollers mounted therein, fingers for 55 controlling said rollers, a shoe provided with radiating slotted arms, a carrier for said fingers disposed within said arms and provided with flanges upon its opposite ends, an interlocking projection between said fingers and 60 carrier to prevent relative rotation thereof, a cam portion at the lower end of said fingers, a pivotal connection between said portion and the upper end of the fingers, a driving-shaft, a controlling-cam upon said shaft hav-

ing a face to effect a consecutive movement 65 of said fingers, and a connection between said cam and said shoe.

30. In a seaming-machine, a seaming-head, seaming-rollers mounted therein, fingers for controlling said rollers, a shoe provided with 70 radiating slotted arms, a carrier for said fingers disposed within said arms and provided with flanges upon its opposite ends, an interlocking projection between said fingers and carrier to prevent relative rotation thereof, 75 a cam portion at the lower end of said fingers, a pivotal connection between said portion and the upper end of the fingers, a driving-shaft, a controlling-cam upon said shaft having a face to effect a consecutive movement 80 of said fingers, a pivoted lever having a pivotal connection with the upper portion of said shoe, a casing mounted on the opposite end of said lever and having a roller therein to bear upon said cam, and tension means 85 for retaining said roller in contact with said cam.

31. In a seaming-machine, a seaming-head, seaming-rollers mounted therein, fingers for controlling said rollers, a shoe provided with 90 radiating slotted arms, a carrier for said fingers disposed within said arms and provided with flanges upon its opposite ends, an interlocking projection between said fingers and carrier to prevent relative rotation thereof, a 95 cam portion at the lower end of said fingers, a pivotal connection between said portion and the upper end of the fingers, a driving-shaft, a controlling-cam upon said shaft having a face to effect a consecutive movement 100 of said fingers, a pivoted lever having a pivotal connection with the upper portion of said shoe, a casing mounted at the opposite end of said lever and having a roller therein to bear upon said cam, a depending rod pivotally connected to said casing, and a weight 105 supported by the lower end of said rod.

32. In a seaming-machine, a seaming-head provided with seaming-rollers, means carried by the head for controlling said rollers, a 110 driving-shaft provided with a cam operatively connected with said controlling means, a driving-gear loosely mounted upon said shaft, a hub secured to said shaft, and a clutch-pin extending from said hub to said 115 gear.

33. In a seaming-machine, a seaming-head provided with seaming-rollers, means carried by the head for controlling said rollers, a driving-shaft provided with a cam operatively connected with said controlling means, 120 a driven gear loosely mounted upon said shaft, a hub secured to said shaft, a clutch-pin extending from said hub to said gear, and means for automatically withdrawing said 125 pin after a rotation of said gear.

34. In a seaming-machine, a seaming-head provided with seaming-rollers, means carried

by the head for controlling said rollers, a driving-shaft provided with a cam operatively connected with said controlling means, a driven gear loosely mounted upon said shaft, a hub secured to said shaft, a clutch-pin extending from said hub to said gear, and a tripper-finger pivotally mounted to normally engage and withdraw said pin.

35. In a seaming-machine, a seaming-head provided with seaming-rollers, means carried by the head for controlling said rollers, a driving-shaft provided with a cam operatively connected with said controlling means, a driven gear loosely mounted upon said shaft, a hub secured to said shaft, a clutch-pin extending from said hub to said gear, a tripper-finger pivotally mounted to normally engage and withdraw said pin, and a lever controlled by an operating-handle and provided with a projection to engage said tripper-finger.

36. In a seaming-machine, a seaming-head provided with seaming-rollers, means carried by the head for controlling said rollers, a driving-shaft provided with a cam operatively connected with said controlling means, a driven gear loosely mounted upon said shaft, a hub secured to said shaft, a clutch-pin extending from said hub to said gear, a tripper-finger pivotally mounted to normally engage and withdraw said pin, a lever controlled by an operating-handle and provided with a projection to engage said tripper-finger, a controlling-flange carried by said hub, and a friction-roller secured to an arm upon said lever for traversing said flange.

37. In a seaming-machine, a seaming-head provided with seaming-rollers, means carried by the head for controlling said rollers, a driving-shaft provided with a cam operatively connected with said controlling means, a driven gear loosely mounted upon said shaft, a hub secured to said shaft, a clutch-pin extending from said hub to said gear, a tripper-finger pivotally mounted to normally engage and withdraw said pin, a lever controlled by an operating-handle and provided with a projection to engage said tripper-finger, a controlling-flange carried by said hub, a friction-roller secured to an arm upon said lever for traversing said flange, a tension device bearing upon the head of said pin, and a beveled face upon said tripper-finger to engage a face upon the head of said pin.

38. In a seaming-machine, a seaming-head, a can-table disposed relatively thereto, a pivoted lever connected to a depending shaft from said table, means extending laterally from said lever, and an operating-lever provided with a cam-lever to engage said means.

39. In a seaming-machine, a seaming-head, a can-table disposed relatively thereto, a pivoted lever connected to a depending shaft from said table, a pin extending laterally from said lever, an operating-lever provided

with a cam-lever to engage said pin, seaming-rollers carried by said head, a driven shaft for actuating said rollers, and a clutch mechanism upon said driving-shaft operatively connected with said controlling-lever for actuation after the raising of the table.

40. In a seaming-machine, a seaming-head, a can-table disposed relatively thereto, a pivoted lever connected to a depending shaft from said table, a pin extending laterally from said lever, an operating-lever provided with a cam-lever to engage said pin, seaming-rollers carried by said head, a driven shaft for actuating said rollers, a clutch mechanism upon said driven shaft operatively connected with said controlling-lever for actuation after the raising of the table, and means for automatically restoring said controlling-lever to its initial position.

41. In a seaming-machine, a standard, a seaming-head thereon, a can-table provided with a shaft mounted for reciprocation toward and from said head, a lever pivotally mounted upon the standard at one end and connected to said shaft at its opposite end, and an operating-lever provided with a cam-surface disposed in the path of a portion of said shaft-lever to engage the same in the travel of the operating-lever.

42. In a seaming-machine, a standard, a seaming-head thereon, a can-table mounted for reciprocation toward and from said head, means for driving said head, a clutch-pin engaging said driving means, a finger to normally hold said pin out of engagement with said driving means, and an operating-lever constructed and arranged to primarily raise the table into seaming position and subsequently withdraw said finger from the clutch-pin.

43. In a seaming-machine, a standard, a seaming-head thereon, a can-table mounted for reciprocation toward and from said head, means for driving said head, a clutch-pin engaging said driving means, a finger to normally hold said pin out of engagement with said driving means, an operating-lever constructed and arranged to primarily raise the table into seaming position and subsequently withdraw said finger from the clutch-pin, and means for automatically throwing said finger into the path of said clutch-pin and for restoring the operating-lever to its initial position.

44. In a seaming-machine, a standard, a seaming-head rotatably mounted thereon, a driven shaft for said head, seaming-rollers mounted in said head, means for actuating the same, a driving-shaft for said means having its gear loosely mounted thereon, a clutch mechanism secured to said last-mentioned shaft for connecting the driving-gear therewith, a counter-shaft below the main driving-shaft and driven therefrom, and a series of reducing-gears and pinions extending from

said counter-shaft to the gear loosely mounted upon the driving-shaft for actuating the seaming-rollers.

45. In a seaming-machine, a seaming-head, means for rotating said head, seaming-rollers each mounted in an independently-reciprocating block upon said head; a pattern-cam carried by said head and connected with each of said blocks for consecutively placing the rollers therein in operative position, a cam-

table beneath said rollers, and means for automatically connecting and disconnecting the seaming-rollers for operation by the pattern-cam.

In testimony whereof I affix my signature 15 in presence of two witnesses.

JOHN A. STEWARD.
